UNITED STATES PATENT OFFICE.

FRANCIS E. AGNEW, OF HUNTINGTON PARK, CALIFORNIA, ASSIGNOR TO MINERVA A. BROTHERTON, OF SANTA BARBARA, CALIFORNIA.

CENTRIFUGAL IMPACT PULVERIZER.

Application filed December 9, 1925. Serial No. 74,291.

My invention relates to centrifugal impact pulverizers and consists of the novel features herein shown, described and claimed.

An object of my invention is to make a centrifugal pulverizer having a plurality of impellers upon a single vertical shaft, so that the material will pass downwardly from one impeller to another.

Another object of my invention is to make a centrifugal pulverizer having a vertical impeller shaft extending through the pulverizing chamber and to provide an improved end thrust bearing and dust excluder for the bearing.

Other objects and advantages will appear from the drawings and specification.

The drawings illustrate the invention.

Figure 1 is a vertical diametrical sectional detail of a centrifugal impact pulverizer embodying the principles of my invention, the view being taken on the line 1—1 of Fig. 2 and looking in the direction indicated by the arrow.

Fig. 2 is a horizontal cross section on the line 2—2 of Fig. 1.

Fig. 3 is an enlarged vertical diametrical sectional detail on the line 3—3 of Fig. 1.

The details of the centrifugal impact pulverizer are as follows:

30 A discharge hopper 1 is circular in plan at its upper end and has a peripheral flange 2 extending all the way around. The base 3 is an annular flange fitting upon the flange 2 and the two flanges are connected by cap screws 4. Supporting plates 5 and 6 extend from the flange 3 at diametrically opposite sides and have supporting ribs 7 and 8. The plates 5 and 6 are adapted to rest upon a suitable foundation for supporting the pulverizer and have bolt holes 9 and 10 for attaching the plates to the foundation.

45 The bearing block 11 is formed as an integral part of the discharge hopper 1. The wall 12 extending downwardly from the flange 2 is funnel shaped, the funnel being mutilated to produce a discharge opening 13 at one side of the bearing block 11 and forms a collecting chamber 14. The extension bearing block 15 extends upwardly from the bearing block 11 into the chamber 14. A circular bore 16 is formed from the lower face of the bearing block 11 and an oil port 17 leads from the outer face of the bearing block 11 into the upper end of the bore 16,

the outer end of the port 17 being closed by a removable plug 18.

The thrust bearing assembly 19 is inserted upwardly into the bore 16 and has a flange 20 fitting against the end of the block 11 and is held in place by cap screws 21. A bore 22 is formed from the upper end of the extension block 15 down to a shoulder 23 and a smaller bore 24 leads from the shoulder 23 to the bore 16. An inner tube 25 is fixed in the bore 24 and extends to the top of the bearing block 15. The impeller shaft 26 extends downwardly loosely through the tube 24 and the thrust bearing member 27 is fixed upon the lower end of the shaft 26 before the assembly 19 is mounted in the bore 16.

The upper end of the block 15 is finished to make an offset shoulder 28. The set collar 29 has a bore 30 to receive the shaft 26 and an enlarged bore 31 to receive the tube 32. The collar is rigidly mounted upon the shaft 26 by set screws 33 or the like and the tube 32 extends loosely in the bore 22 and loosely around the tube 25 to near the shoulder 23. The lower face of the set collar 29 is counterbored to make an end ring 34 cooperating with the offset shoulder 28 to make a staggered joint between the collar 29 and the bearing block 15 and this staggered joint with the tubes 32 and 25 operating in oil or grease serves to exclude the pulverized dust of the chamber 14 from the thrust bearing 19.

55 The casing 35 is formed integral with the base 3 and extends upwardly and has an annular flange 36 around its upper end. The casing 35 and base 3 mounted upon the flange 2 leaves an annular shoulder 37 at the top of the hopper 1. The casing 35 is circular in plan and forms a circular chamber 38. The cylindrical breaker or impact plate 39 fits in the lower end of the casing 35 upon the shoulder 37 and has a corrugated inner face 40. The plate 39 is preferably made of manganese steel. The intermediate portion 41 of the shaft 26 is hexagonal in cross section.

100 The impeller disc 42 has a hub 43 with a bushing 44 cast into the hub and fitting the hexagonal portion 41 of the shaft. The circular web 45 extends outward from the lower end of the hub 43 and straight impeller blades 46 extend in a radial direction

along the upper face of the web 45, preferably near its periphery and the upper face of the web 45 is slightly inclined from the hub outwardly and downwardly. The impeller disc 42 is in the plane of the impact plate 39. The funnel 47 fits tightly within the shell 35 and rests upon the impact plate 39. The spacing sleeve 48 fits upon the hexagonal portion of the shaft 26 against the hub 43. The second impeller 49 fits upon the shaft 26 against the sleeve 48. The impact plate 50 fits in the shell 35 upon the funnel 47. The second funnel 51 fits in the shell 35 against the impact plate 50. The second sleeve 52 fits upon the shaft 26 against the impeller 49. The third impact plate 53 fits in the shell 35 against the funnel 51. The third impeller 54 comprising a disc having impeller blades fits upon the shaft 26, against the sleeve 52. The third funnel 55 fits in the shell 35 against the impact plate 53. Screw threads 56 are formed upon the shaft 26 above the impeller 54 and jamb nuts 57 and 58 fit upon the threads 56 against the hub of the impeller 54 to tighten the impellers against the said collar 29. A plate 59 fits in the shell 35 against the top of the funnel 55 and has a central opening through which the shaft 26 extends and has a second opening through which the feed spout 60 extends. The cap ring 61 fits upon the annular flange 36 and slightly overlaps the edge of the plate 59 and is held in place by cap screws 62. The portion 63 of the shaft 26 above the threads 56 is round and smooth and a belt pulley 64 is secured upon this portion of the shaft above the cap ring 61.

Arms 65 extend upwardly and inwardly from the cap ring 61 and a bearing block 66 is formed integral with the upper ends of the arms 65. The feed spout 60 has a funnel shaped upper end 66 and is inserted through one of the arms 65 and through the plate 59 to discharge the material to the funnel 55 and to the upper impeller 54, there being a flange 67 extending from the spout 60 and bolted to the arm 65 to hold the spout securely in place. The chamber 68 is formed from the upper end of the bearing block 66 and the ball bearing assembly 69 is mounted in this chamber around and upon the upper end of the shaft 26 and a cap 70 is secured to the bearing block by cap screws 71 to cover the bearing 69. The driving belt 72 passes around the pulley 64, one flight of the belt being on one side of the arm 65 and the other flight on the other side.

The centrifugal impact pulverizer thus constructed is adapted to pulverize lime-stone, talc, quartz, ores, and the like, to produce various mineral products, and the material to be pulverized is broken up into comparatively small pieces and continuously fed

through the spout 60 and funnel 5 to the impeller 54 from which it is discharged against the impact plate 53 and passes downwardly through the funnel 51 to the central portion of the impeller 49 and is again thrown against the impact plate 50 and passes downwardly through the funnel 47 to the central portion of the impeller 42 and is again thrown against the impact plate 39 and passes downwardly to the chamber 14 and is discharged through the passage 13. Of course the impellers are to be operated at a high rate of speed and the successive impeller actions will reduce suitable ore or other material to a fine powder and if all of the material is not sufficiently reduced it may be separated and run through the machine again.

Thus I have made a centrifugal impact pulverizer, comprising a discharge hopper having a central bearing block and a discharge opening at one side of the bearing block, an impeller shaft mounted in a thrust bearing in the bearing block, means for excluding dust from the thrust bearing, a shell mounted upon the hopper, an impact plate mounted in the shell, an impeller mounted upon the shaft to discharge against the impact plate, a funnel mounted in the shell upon the impact plate and forming a pulverizing unit, there being a plurality of said pulverizing units in the shell and upon the shaft above the first unit, and a discharge spout leading to the top unit, so that the material will pass from one impeller unit to the next and then to the discharge hopper.

Various changes may be made without departing from the spirit of my invention as claimed.

I claim:

1. A centrifugal impact pulverizer comprising a discharge hopper having a central bearing block and a discharge opening at one side of the bearing block, a vertical impeller shaft mounted in a thrust bearing in the bearing block, a vertical shell mounted upon the hopper, a cylindrical impact plate mounted in the shell, an impeller having a horizontal disc with radial, vertical blades at its outer edge spaced from the shaft mounted upon the shaft to discharge against the impact plate, a funnel mounted in the shell upon the impact plate discharging near the center of the disc, said impact plate, impeller and funnel forming a pulverizing unit, there being a plurality of said pulverizing units in the shell above the lowest unit, and a discharge spout leading to the top unit so that material will pass from one impeller unit to the next and then to the discharge hopper.
2. In a centrifugal impact pulverizer, a vertical shell, a vertical impeller shaft in the shell, an impeller upon the shaft having a horizontal disc with blades adjacent its outer edge, an impact plate in the shell in the

5 plane of the impeller, a funnel in the shell discharging to the impeller substantially inside the blades, a second similar impeller upon the shaft upon the funnel, a second similar impact plate in the shell in the plane of the second impeller, and means for discharging material to the central portion of the second impeller.

10 3. A centrifugal impact pulverizer comprising in combination a vertical shell having a series of cylindrical breaker rings therein, a vertical shaft having a series of flat horizontal impeller discs mounted thereon, vertical impeller blades mounted on some 15 of the discs adjacent their outer edges, and a series of funnel-like constructions to feed material from the outer periphery of an upper impeller disc to the central portion of an impeller disc there next below.

20 4. A centrifugal impact pulverizer comprising in combination a vertical shell having a series of stationary cylindrical breaker rings therein, a vertical shaft having a series of horizontal impeller discs mounted thereon, impeller blades mounted on some of the 25 discs and a series of hopper-like constructions adapted to feed material from the outer periphery of an upper impeller disc to the central portion of an impeller disc there next below.

25 5. A centrifugal impact pulverizer comprising in combination a vertical shell having a plurality of cylindrical breaker rings positioned therein at different elevations, a vertical shaft centrally mounted in the shell, a series of horizontal impeller discs mounted

on the shaft, impeller blades extending upwardly from the surfaces of the discs adjacent the periphery of the discs and spaced from the center, said blades being adapted 40 to throw material radially outwardly against the breaker rings, a hopper at the top of the shell, and a series of secondary hoppers inclined inwardly from the breaker rings towards the center of the impeller discs, adapted 45 to discharge material on said discs inside the impeller blades.

6. In a centrifugal impact pulverizer, a vertical shell having a breaker ring, a vertical shaft, an impeller disc mounted thereon, a plurality of impeller blades extending vertically and radially outwardly of said disc adjacent its periphery and spaced from its center, a hopper-like structure positioned above the disc, having a discharge above the 50 disc adjacent the shaft and radially inwardly of the impeller blades.

7. In a centrifugal impact pulverizer, a vertical shell, a stationary cylindrical breaker ring mounted therein, a central vertical shaft 60 with a horizontal impeller disc thereon, a plurality of impeller blades, such blades extending upwardly from the disc adjacent its periphery, and being positioned in a radial direction, the inner edge of the blades being 65 spaced from the shaft, and a hopper positioned above the disc, having a discharge on to the disc radially inwardly of the inner edges of the impeller blades.

In testimony whereof I have signed my 70 name to this specification.

FRANCIS E. AGNEW.
